CATHETER

Paul A. Raiche, North Providence, R. I., assignor
to Davol Rubber Company, a corporation of
Rhode Island

Application November 16, 1951, Serial No. 256,756

5 Claims. (Cl. 128—349)

1

The present invention relates to surgical appliances, and has particular reference to a novel construction for a catheter.

The principal object of the invention is to provide a catheter construction of the inflatable balloon type which has no distal tip or projection.

Another object of the invention is to provide a balloon catheter construction having an axial drainage channel with an open end.

A further object of the invention is to provide a catheter construction having a foraminated distal end.

An additional object of the invention is to provide a catheter having a reinforced foraminated distal end for engagement by a stylet.

With the above and other objects and advantageous features in view, the invention consists of a novel article of manufacture more fully described in the detailed description following, in conjunction with the accompanying drawings, and specifically defined in the claims appended thereto.

In the drawings,

Fig. 1 is a side elevation of a catheter embodying the invention;

Fig. 2 is an enlarged view of the distal end;

Fig. 3 is a section on the line 3—3 of Fig. 1; and

Fig. 4 is a perspective view of the distal end showing the application of cloth inserted latex strips to the distal end of the catheter body before mounting of a balloon thereof.

It has been found desirable to provide a catheter construction of the balloon type which has no distal tip, as some patients having inflamed or sensitive bladders react unfavorably to the normal type of balloon catheter which has a distal drainage tip. To this end, I provide the catheter with a terminal opening, and I mount transverse reinforcement strips across the opening so that an insertion stylet contacts the strips, whereby a foraminated drainage opening results which is closely adjacent the balloon.

Referring to the drawings, the catheter 10 has the usual tubular body 11, with a drainage channel 12 and an inflation wall channel 13, the drainage channel having an outflow terminal connection 14 and the inflation wall channel having an angularly positioned inflation connection 15 tapered to receive a closure plug or the like. An inflatable balloon 16 is positioned on the distal end 17 of the catheter, and a communicating opening 18 connects the inflation wall channel 13 with the interior of the balloon 16 in standard manner. The distal end 17 of the catheter is open and substantially flush with the

2

outer surface of the balloon, and has a foraminated closure formed of crossed strips 19, 20 of cloth inserted latex or rubber which provide foraminated drainage inlets 21 to the drainage channel. The cloth inserted strips are of standard type, manufactured by dipping cloth into latex or rubber solution to encase the cloth with rubber.

The catheter 10 is preferably manufactured by dipping a grooved body form into latex solution and inserting a preformed inflation tubing or an inflation tube form which is dipped, the communicating opening 18 being formed by burning, in standard manner. When the body and the inflation channel are thus formed, the cloth inserted latex or rubber strips 19, 20 are placed over the distal end 17, in crossed relation and cemented in place to provide a thickened portion 22, and the assembly is lightly dipped in latex or the like to cover the body, the strips 19, 20 and the spaces on the body end between the strips, whereby a preformed balloon blank is positioned over the distal end with the open end of the body in substantially the plane of the outer end of the balloon, and cemented in place. It is sometimes desirable to lightly dip the distal end in latex or the like to smoothly finish the distal end, the openings 21 being cleaned if necessary.

The above described manufacture provides a novel balloon catheter having no distal drainage tip and a foraminated open end, the foraminated open end having a strong centrally positioned stylet receiving portion. Although I have described a specific catheter construction, it is obvious that changes in the article to meet different catheter requirements may be made without departing from the spirit and the scope of the invention as defined in the appended claims.

I claim:

1. A balloon catheter having an elongated body, a drainage passage, a balloon inflation channel, and an inflatable balloon mounted on the distal end of the body, the wall of said body at the distal end having an opening communicating the inflation channel with the interior of the balloon, the end of the body having cross strips of cloth inserted rubber in substantially the plane of the outer end of the balloon and spaced to provide a foraminated inlet to the drainage passage.

2. A balloon catheter having an elongated body, a drainage passage, a balloon inflation channel, and an inflatable balloon mounted on the distal end of the body, the wall of said body at the distal end having an opening communicating the inflation channel with the interior of the balloon,

3

the end of the body having crossed strips of cloth inserted rubber providing a centrally positioned stylet receiving portion in substantially the plane of the outer end of the balloon, said crossed strips being spaced to provide a foraminated inlet to the drainage passage.

5

3. A balloon catheter having an elongated body, a drainage passage, a balloon inflation channel in the body wall, and an inflatable balloon mounted on the distal end of the body, the wall of said body at the distal end having an opening communicating the inflation channel with the interior of the balloon, the end of the body being in substantially the plane of the outer end of the balloon and having a foraminated stylet receiving closure to provide an inlet to the drainage passage.

4. A balloon catheter having an elongated body, a drainage passage, a balloon inflation channel in the body wall, and an inflatable balloon mounted on the distal end of the body, the wall of said body at the distal end having an opening communicating the inflation channel with the

10

15

interior of the balloon, the end of the body being open and having crossed strips of cloth inserted rubber in substantially the plane of the outer end of the balloon, said strips being spaced to provide an inlet to the drainage passage.

4

5. A balloon catheter having an elongated body, a drainage passage, a balloon inflation channel in the body wall, and an inflatable balloon mounted on the distal end of the body, the wall of said body at the distal end having an opening communicating the inflation channel with the interior of the balloon, the end of the body being open and having crossed strips of cloth inserted rubber providing a centrally positioned stylet receiving portion in substantially the plane of the outer end of the balloon, said strips being spaced to provide an inlet to the drainage passage.
